CONTAINER

Bernard E. Rosenberg, Fair Haven, N. J.

Application March 6, 1951, Serial No. 214,189

1 Claim. (Cl. 137—576)

(Granted under Title 35, U. S. Code (1952),
sec. 266)

1

The invention described herein may be manufactured and used by or for the Government for governmental purposes, without the payment of any royalty thereon.

The present invention relates to a container and more particularly to an improved container capable of use where two fluids are to be mixed and dispensed.

In certain field operations wherein particular power units are used, the requirement often arises that a fuel mixture of fixed proportions of gasoline and oil be used. Heretofore, this has been accomplished by measuring a fixed amount of oil in a graduated measuring container and pouring such oil into the container of gasoline. Such practice involved the carrying of measuring containers and the loss of time in preparing the required mixtures.

It is an object of the invention to furnish a container which is particularly adapted, though not so limited, for dispensing a gasoline and oil mixture such as is commonly employed in connection with certain types of internal combustion engines.

A further object of the invention is to provide a container in which the two fluids contained therein can be mixed without the use of any particular skill, in such a manner that the fluids will be thoroughly mingled.

A still further object of the invention is to provide a container so constructed that the contents thereof will be effectively protected from contamination by dirt, grit, etc.

Still another object is to provide a mixing container that is relatively inexpensive to construct and which will include relatively few parts.

With these and other objects in view, reference is made to the attached drawing, illustrating one embodiment of the invention, and in which,

Fig. 1 is a perspective view of a can embodying the invention, and partly broken away, showing the tubular mixing compartment;

Fig. 2 is a view of the tubular mixing compartment, partly in cross section, and partly in elevation;

Fig. 3 is a top view of the spout and its adjacent stops.

Referring to the drawing, there is shown a container 11 of conventional rectangular shape, preferably of one gallon capacity. The container 11 is provided with a carrying handle 13 on its top surface 12. Within the container 11 and secured to the underside of the top cover

2

12 of the container, is a cylindrical tube 15, having a closed bottom end. Tube 15 is provided with two pairs of openings or holes 17, one pair of holes being disposed adjacent the bottom or lower end of the tube, while the other pair is disposed close to the top or upper part of the tube. The openings 17 of each pair of holes are spaced 180° from each other.

Confined within the cylindrical tube 15 and rotatable therein is a cylindrical tube 19, having an outside diameter of such size so as to fit snugly within the tube 15. Tube 19 is also provided with two pairs of holes or openings 21, one pair of openings adjacent the top edge of the tube and the other pair adjacent the lower edge of the tube. The openings 17 of tube 15 and openings 21 of tube 19 are similarly arranged so that the openings 21 of the movable tube 19 can be brought into register with the openings 17 of the fixed tube 15. Conversely, when the tubes are in non-registering position, that is, the openings of each tube are not concentric, the two tubes together form a compartment of fixed liquid capacity. The upper portion of inner tube 19 is provided with an outwardly and downwardly extending threaded flange 23, which threadably engages a threaded neck 25 of the container 11. Secured to and emerging outwardly from the base of the threaded flange 23 is a substantially channel-shaped pouring spout 27. It will be obvious that movement of the spout will effect rotational movement of the inner cylindrical tube 19. Secured to the surface 12 of container 11 are two stops 29, 31, which serve to indicate the relative position of the movable tube 19 to that of the fixed tube 15 and also to limit the swing of the spout to 90°. As shown in Fig. 3, there is applied to the top cover 12 of the container adjacent the stop 29, a designation or marking labeled "Oil." This serves to indicate that when the spout 27 is against said stop, the holes 17 and 21 of tubular members 15 and 19 are not in register and that a compartment of fixed capacity is available for the pouring of oil therein, as shown in dotted outline. Likewise, a designation labeled "Gas" is applied adjacent the stop 31, which serves to indicate that when the spout is against said stop, the holes 17 and 21 are in register and that liquid can flow through the tubes 15 and 19 into the container 11. In lieu of such designations, any other appropriate markings may be applied, such as, for example, "closed" adjacent stop 29, indicating that the holes are not in register; or "open" adjacent stop 31, indicating that holes

are in register. To prevent any leakages through the top of the can, there is provided a gasket 33, made of a material not affected by either gasoline or oil, between the top surface 12 and the flange 23 of the tube 19. If it becomes necessary to ship or carry the container, any appreciable distance, a screw cap (not shown) may be put on the threaded neck 25.

The container described above is used in the following manner. Starting with an empty container, the spout 27 is turned until it lies flush against the stop 29. This position of the spout insures that the openings 17 and 21 of the tubes 15 and 19 are not in register. Oil is then poured through the neck 25 until the oil level reaches the lower part of the neck. The snug fit of the inner tube 19 within the outer tube 15 is such as to prevent any oil from seeping into the container 11. The spout is then rotated 90° until the spout is stopped from further movement by stop 31. In this position, the holes 17 and 21 are in register, thus allowing the oil, heretofore confined, to flow into the container 11. With the spout in this position, gasoline is poured into the container until it is full. In this manner an intimate mixture of fixed amounts of gasoline and oil has been prepared which can then be easily poured from the container.

While there has been described one particular form of the invention, it is obvious that changes in design can be made without departing from the spirit and scope of the invention.

I claim:

A measuring device comprising a container provided with an opening in its top surface, a mixing compartment partly positioned within said opening and within said container, said mixing compartment comprising an outer tube secured at its proximal end to the underside of said top surface of said container and closed at its distal end and provided with a plurality of opposing openings spaced 180° from each other, an inner tube rotatable within said outer tube and provided with opposing openings spaced 180° from each other that are in register with the openings of said outer tube when said inner tube is rotated to a predetermined position, said inner tube terminating in a flange that threadably engages a neck on said top surface of said container, a pouring spout secured to said threaded flange and means on said top surface of said container to limit the rotational movement of said spout.
